MACHINE FOR SEALING METAL BOXES OR CANS.

1,136,401.

Specification of Letters Patent.

Patented Apr. 20, 1915.

Application filed April 15, 1911. Serial No. 621,360.

To all whom it may concern:

Be it known that we, JOHN C. BOWERS and EARL E. BARBER, both of Boston, in the county of Suffolk and State of Massachusetts, and ALBERT D. GROVER, of Malden, in the county of Middlesex, in said State, have invented a new and useful Improvement in Machines for Sealing Metal Boxes or Cans, of which the following is a specification.

10 This invention relates to the sealing of metal boxes or cans and as described is applied to the sealing of boxes of the shape generally used for packing sardines. Such boxes must be hermetically sealed and heretofore they have been usually sealed by a process which includes the use of solder either in attaching the cover and box together or in the application of a sealing strip by which the joint between the cover 15 and the box is closed. The United States patent to John C. Bowers, No. 867,239, dated October 1, 1907, describes and shows a hermetically-sealed receptacle or can which has a dished cover, the dishing of which fits the 20 interior of the box and the edge of which forms a flange adapted to register with the flange of the box, the whole being sealed by a strip of metal U-shaped in cross section by means of which the flanges of the box and 25 cover are clamped together. The machine hereinafter described is especially adapted for sealing such a receptacle, and for this purpose it cuts and forms a metallic strip and applies it to the flanges of a box and 30 cover of the character referred to with sufficient pressure to form a hermetically-tight joint of the character specified in the said patent.

While we have shown and described hereinafter the best form of our invention now known to us, certain changes in detail will undoubtedly occur to one skilled in the art and may be made without departing from the spirit of our invention. Moreover, we 45 have shown our invention especially adapted to seal a box of oblong shape, but it will be seen that by changing the shape of the formers or work-holders by which the box is held the machine can equally well be used 50 for applying the strip to so hermetically seal a round, oval or other shaped box.

Our invention will be understood by reference to the drawings in which is shown a practical embodiment thereof and which comprises a work-holder adapted to present 55 the work, whatever its shape, to the sealing rolls by means of which the strip is caused to seal the edges of the box and cover, and means for forming the strip which is to form the seal and cut it in proper lengths 60 as needed, and also for feeding the strip, all these being shown in their preferred form and with the preferred form of mechanism by which each is caused to perform its function.

Figure 1 is a plan of such a machine. Fig. 2 is a front elevation thereof. Fig. 3 is a section on line 3—3 of Fig. 1. Figs. 3^a and 3^b are details showing cams and their levers described below. Fig. 4 is an enlarged section on line 4—4 of Fig. 2. Fig. 5 is an enlarged view of the sealing rolls in action, Fig. 5^a being a magnified detail showing the sealing operation. Fig. 6 is a section on line 6—6 of Fig. 1. Fig. 6^a is a section on 75 line 6^a—6^a of Fig. 6. Fig. 6^b is an elevation showing the shape of the cut given the sealing strip by the cutting tool. Fig. 7 is an enlarged plan of the strip guides. Fig. 8 is a section on line 8—8 of Fig. 7. Fig. 9^a is an enlarged section on line 9—9 of Fig. 1. Fig. 10 is a cross section on line 10—10 of Fig. 9. Fig. 11 is a plan of the strip-feeding mechanism. Figs. 12, 13 and 14 are sections on lines 12—12, 13—13 and 14—14, respectively, of Fig. 11. Fig. 15 is a plan of the forming rolls. Figs. 16, 17, 18 and 19 are sections on lines 16—16, 17—17, 18—18 and 19—19, respectively, of Fig. 15. Fig. 20 shows a modification in which power is 90 applied to both the lower former as well as to the upper former, as will be described below, and Fig. 21 is a rear view thereof to show the power-transmitting arrangement.

A is a table on which are mounted the 95 various operating parts.

B is the power shaft mounted in bearings a upon a bracket A¹ bolted to the table, and C is the main shaft mounted in bearings a¹ also supported on the table A. The power 100 shaft B carries a pulley B¹ to receive a belt and it also carries a pinion B² which

meshes with a gear C^1 on the main shaft C . A clutch mechanism indicated at C^2 connects the gear C^1 with the main shaft C , C^3 being a rod forming a part thereof. Such a mechanism operated by a treadle is a well known element of machines and as it forms no part of this invention, need not be otherwise described than to say that when the treadle is depressed the clutch is thrown in and the machine operates, the clutch mechanism being released automatically.

At one end of the table is mounted a head A^2 which for convenience is made in two parts bolted together by bolts A^3 . It carries bearings for the sealing roll shafts and also supports the gear by which the sealing rolls and the work-holder or former are operated.

The main shaft C carries an intermittent gear D by which an intermittent movement is given to the work-holder mechanism, the crank arm E by which the strip feeding and forming mechanisms are operated, a cam F by which the strip-cutting mechanism is operated and the upper sealing roll is lifted to insert and release the work, and a cam H by means of which the upper member of the work-holder is lifted for the insertion and release of the box and its cover.

The gear D is mutilated for substantially half its periphery. Its teeth mesh with an intermittent gear D^1 also mutilated as at d^1 to ride upon and be locked by the mutilated surface d of the gear D . The gear D^1 is mounted to turn on a stud D^2 supported on a bracket or other support d^2 attached to the table A . On the stud D^2 is also mounted a gear D^3 in mesh with a pinion D^4 on a stud D^5 fixed in the head A^2 . The pinion D^4 is pinned to an intermediate gear D^6 also mounted on the stud D^5 so that the pinion and gear turn together. The intermediate gear D^6 is located between and in mesh with gears D^7 , D^8 .

The gear D^7 is mounted on one end of the shaft J which runs in bearings j in the head A^2 . The other end of the shaft J carries the lower sealing roll L . The shaft J also carries a pinion J^1 which meshes with a pinion K^1 on the shaft K . This shaft K carries at one end the upper sealing roll L^1 which is located to coöperate with the lower sealing roll L . The shaft K is supported to rotate in a rocking bearing K^2 which is pivoted at k in the head A^2 so as to allow its free end a slight vertical movement sufficient to allow the upper sealing roll to separate from the lower sealing roll to insert the work, as below described.

The periphery of the working edge of the sealing roll L is smooth to act as a pressure table upon which the work lies, the periphery of the upper sealing roll being shaped to give the necessary pressure to seal

the strip in the closing of the can. This will be understood from Figs. 5 and 5^a where M is the receptacle, M^1 being the cover. The flange of the receptacle is lettered m and the flange of the cover m^1 , the strip being lettered P . Preferably the flange of the cover is turned back on itself as shown at m^2 thus forming a shoulder, and the upper sealing roll L^1 has two diameters forming two surfaces, one the surface l which in the action of the tool runs upon the strip P pressing it and the turned-over edge of the cover as well as the flange of the cover itself against the flange of the receptacle or box and the other l^1 of larger diameter which turns the edge of the strip over the shoulder formed by the turned over portion m^2 of the flange and also the remainder of the strip against the flange, thus completely sealing the can. For this purpose very heavy pressure is required, say of several hundred pounds, and in the form of our invention shown to secure this heavy pressure we provide a spring K^3 located in a cavity K^4 in the head A^2 . The lower end of the spring K^3 rests upon the rocking bearing K^2 of the upper sealing roll shaft and is brought forward as near to the upper sealing roll as is practicable. The upper end of the spring K^3 receives a follower K^5 on which rests an adjusting screw K^6 which passes up through a threaded opening in the head, its head being pierced so that the screw may be easily turned by a pin to adjust the position of the follower K^5 within the cavity and so adjust the strength of the spring K^3 , and a check nut K^7 is provided to hold the screw in place when it has been properly adjusted. The intermediate gear D^6 is also in mesh with a gear D^8 on one end of the shaft Q which also runs in the head A^2 . At its further end this shaft Q carries a bevel gear Q^1 which meshes with a bevel gear Q^2 on a vertical shaft Q^3 supported at its upper end in an arm A^4 forming a part of or attached to the head A^2 and supported against gravity by the hub of the bevel gear Q^2 which rests on the top of a bearing forming a part of the head A^2 . At its lower end the shaft Q^3 carries a pinion Q^4 which meshes with the gear teeth r on the periphery of the upper member R of the work-holder.

The work-holder as shown comprises two members, an upper member which carries the gear teeth r above referred to and by which the work-holder is rotated, and a lower member S against which the upper member clamps the work and which consequently rotates with the upper member when the work is in place.

In Figs. 20 and 21 we have shown a modification of our invention which will be described below in which the lower as well as the upper member of the work-holder is rotated positively. The machine as shown

is adapted to seal a metallic receptacle shaped like an ordinary sardine box having one diameter longer than the other, and for this purpose yielding means are provided for holding the upper member R constantly in mesh with the teeth in the pinion Q⁴. The member R comprises a plate R' adapted to fit with accuracy in the cover of the box to be sealed and connected by a neck R² to the pattern or former piece R³ which carries the gear teeth r, this pattern or former being of the same shape and approximately the same size as the box to be sealed. The upper surface of this former is recessed as at r¹ and within the recess runs a roll r² carried by a stud r³ supported in a bearing r⁴ in an arm r⁵ bolted to the side of the head A². The attachment of the arm r⁵ to the head A² is preferably adjustable so that the same bearing r⁵ may be used with different formers. The arm must be so adjusted that the roll shall hold the gear teeth r in mesh with the gear Q⁴ and the recess r¹ is of sufficient depth and the gear Q⁴ of sufficient breadth to allow the upper member R to be lifted and lowered again in the process of clamping the box against the member S.

The clamping operation is accomplished as follows:—The neck R² is circular in cross section and is held in a bearing R⁴ carried by an arm R⁵ attached to a sleeve R⁶. A stud R⁷ sets in this sleeve and is supported in an enlargement R⁸ in a bracket R⁹ which bracket swings on a pin R¹⁰ carried by a second bracket R¹¹ pivotally hung on a stud R¹² carried by the plate A² supported under the table A (see dotted lines, Fig. 1). Thus the bracket R⁹ has a movement around the pin R¹⁰ and the bracket R¹¹ which carries the pin R¹² has a movement around the stud R¹², thus giving to the work-holder sufficient freedom of movement for its teeth r to keep in mesh with the gear Q⁴ during its entire rotation, whatever may be its shape. The lower member S is mounted on top of a stud S¹ which is supported to turn in the bracket R¹³. It has a rim s around its upper edge which forms a cavity to receive the work, and a raised portion s¹ conforming somewhat with the usual cavity on the under side of the box to be sealed so as to keep it from being crushed or changing shape during the sealing operation.

The sleeve R⁶ has mounted on it two interlocking collars r¹⁴, r¹⁵ through which the stud R⁷ passes. The lower one of these collars r¹⁴ is slotted as shown in Fig. 10 and through each slot passes a screw r¹⁶ which connects the upper collar r¹⁵ with the sleeve R⁶ so that they move together and have a slight movement independent of the collar r¹⁵. The collar r¹⁵ has a handle r¹⁷ projecting from it and also has a toe r¹⁸ for purposes to be below described.

To the upper end of the stud R⁷ is attached

by a screw R¹⁹ a steady pin R²⁰ and cap piece R²¹ to which is attached by the screw R²² one end of the spring R²³ the other end of which is attached to the handle r¹⁷. This spring is under considerable compression so that it depresses the sleeve R⁶ and hence by means of the arm R⁵ the upper member of the former R so that it will clamp the box M and its cover M¹ between the plate R⁹ and the lower member of the work-holder S. The spring R²³ also has a tensional stem which normally holds the collar r¹⁵ in the position shown in Fig. 10 in which case the toe r¹⁸ lies in the position shown in Fig. 1.

The strip P, by which the box M and cover M¹ are bound together, is a narrow, flat, metallic strip as shown in cross section in Figs. 12 and 13. It is taken from the roll (not shown) and fed, cut and formed by an intermittent process, the result of the operations of the following mechanisms:—The crank arm E on the main shaft C is connected by a connecting rod P¹ to a point on a rocker arm E¹ approximately midway between its extremities, the connection being slotted somewhat to give the connecting rod adjustment with relation to the rocker arm. This rocker arm is mounted at one end on a rock shaft Y mounted in a suitable support A² bolted to the table A, its other end being connected by a connecting rod U¹ with one end of a rack E² which slides in ways A³ on the table A. On the table A are also mounted three pairs of vertical shafts T, T¹, U, U¹ and V, V¹. Each shaft T, U and V carries a pinion T², U² and V², respectively, and each pinion rotates with it and at its lower end each shaft T, U and V carries a gear attached thereto. The gears on shafts T and U are lettered T³ and U³, respectively, and each gear is in mesh with the corresponding gear T⁴ and U⁴. (See Figs. 14, 15 and 16.) The shaft V carries a corresponding gear in mesh with a gear on shaft V¹, these gears not being shown because of their similarity in construction and function with corresponding gears on the shafts T, T¹, U, U¹. The movement of the rack in either direction, therefore, will give to the shafts T, T¹, U, U¹ and V, V¹ a corresponding movement. Cross braces T⁵ and U⁵ center the inner ends of the shafts T, T¹ and U, U¹, collars V⁵ holding the braces in place on the shafts as shown. The shafts V, V¹ are similarly braced and a vertical section of these shafts and their moving mechanism would be identical with the mechanism operating the shafts U and U¹ as shown in Fig. 16, and so it is not shown.

Each shaft T¹, U¹ and V¹ has an enlargement corresponding in diameter and thickness with the pinions T², U² and V² on the companion shafts T, U and V. These enlargements serve with the pinions T², U²

and V^2 to support the various shafts in the table, the enlargements on shafts T^1 and U^1 being shown at T^6 and U^6 and the enlargement on shaft V^1 being identical with those shown on T^1 and U^1 . Above these pinions and enlargements are mounted ratchets t , u and v which are engaged by pawls t^1 , u^1 and v^1 mounted in pairs on the under side of feed rolls t^2 and forming rolls u^2 and v^2 , this arrangement being such that when the rack is moved in the direction of the arrow (see Figs. 4, 11 and 15) the rolls will all be moved by the pawls in a direction to feed and form the strip, but when the rack reverses its movement the rolls will be stationary. The strip P in the first instance is pushed by hand between guide rolls w , w mounted on guides W , W , and passes a holding pawl w^1 carried by one of the guides W and between the feed rolls t^2 and w , w . The holding pawl w^1 is merely a pawl with a roughened edge to engage the strip and pivoted within a suitable cavity in one of the guides W , the roughened edge of the pawl being held against the strip by the spring w^2 so as to prevent the strip from springing back or being drawn out accidentally from between the guides. As shown the guides W , W , are mounted on a plate X bolted to the table A .

In order to adjust the width or space between the feed rolls t^2 , t^2 , so that the rolls may be separated to receive the end of the strip when the strip is first introduced into the machine and also so that they may bear upon the strip with sufficient tension to feed it properly, we preferably mount the upper ends of the shafts T , T^1 in a crossbar T^{61} which is provided with an opening to receive the upper end of the shaft T and also is slotted to receive a slide piece T^7 one end of which forms with a corresponding curved surface of said slot a bearing for the upper end of the shaft T^1 . The slide piece T^7 has a flange T^8 which cooperates with a plate T^9 secured thereto (see Fig. 14) to hold the slide piece in place. A continuation T^{10} of the crossbar T^{61} forms a support for a spiral spring T^{11} which is compressed between a collar T^{12} bearing on the flange T^8 and plate T^9 and a collar and nut T^{13} on the end of the part T^{10} . The spring thus adjusts the slide piece T^7 against the end of the shaft and by loosening the tension of the spring T^{11} the shaft is allowed to spring slightly out of vertical position thus separating the rolls sufficiently to enable the end of the strip to be pushed between them. For this purpose the opening in the table A to receive the shaft T^1 is of sufficient size with relation to the diameter of the shaft T^1 where it bears upon the said opening to allow it the slight vertical movement required.

There are two sets of forming rolls u^2 , u^2 and v^2 , v^2 . The peripheries of the rolls u^2 , u^2 are shaped to give to the strip a preliminary bend on a line slightly below its middle for the reason that the upper portion of the finished strip has more surface to cover in sealing the cover and box together than the lower portion. For the purpose of giving the strip its proper shape one of the rolls u^2 has a projecting surface and the other a retreating surface forming rotary dies between which the strip is drawn and by which it is given its preliminary bend. The shape of these surfaces will be understood by reference to Fig. 16. The rolls v^2 , v^2 have complementary surfaces which are shaped to complete the forming of the strip as will be seen from Fig. 18. Between the pairs of rolls u^2 and v^2 are guides W^1 , W^1 as shown in cross section in Fig. 17, and beyond the rolls v^2 are guides W^2 , W^2 shown in cross section in Fig. 19, one of which W^2 is for convenience made shorter than the other W^3 , the latter extending substantially to the point where the strip engages the box. The guide W^2 has a roll w^3 adjustable therein and forming part of the surface which guides the outer or peripheral edge of the strip and serves by its frictional contact with the said edge of the strip to straighten the strip. A pawl w^4 , similar in construction to the pawl w^1 , prevents the strip from withdrawal in the way below described.

The strip is cut to proper length by the action of a punch G and die G^1 , the punch being operated by a cam lever G^2 mounted at one end to turn on the shaft H^2 and at the other end pivoted to the connecting rod G^3 . This connecting rod is pivotally connected to the bell crank lever G^4 fulcrumed in a bracket G^5 attached to the front of the table A , the upper end of the bell crank lever G^4 lying in a slot in the punch carriage G^6 . This carriage is mounted on a block G^7 mounted on the edge of the table A , the block having ways and a top plate G^8 forming a passage in which the carriage slides. The punch G is mounted in a slot in the carriage G^6 and is held in place therein by a set screw g . Opposite the carriage is a stationary plate G^9 having a die G^1 suitably secured thereto against one edge of which the punch G acts and a downward passage g^3 through which the metal cut off by the die will fall out of the cutting mechanism. The cutting edges of the punch G are shaped as shown in Fig. 6^a and the punch is adapted not only to sever the strip but to cut from its rear end a short section so as to leave a tongue p (see Fig. 6^b) which performs no part of the sealing function, but acts as a tab by means of which the strip may be pulled off in opening the box. To operate this cutting mechanism the cam lever G^2 carries a projection g^4 which is engaged at the proper time by a roll g^5 on the side 190

of the cam F (see Fig. 3^a). A spring g^2 attached at one end to a standard g^1 on the table and at the other end to the cam lever G^2 holds the projection g^1 against the roll g^2 . The cam F also performs the function of lifting the rocking bearing K^2 for the upper sealing roll. For this purpose the edge of the cam F engages a slot f on the cam lever F^2 mounted on the end of the rock shaft F^1 which is supported in bearings F^3 in the table A . This shaft carries at its other end an arm F^2 the outer end of which lies under the rocking bearing K^2 so that at the proper moment a slight depression of the arm F^2 will cause a corresponding lifting of the arm F^1 and consequently of the rocking bearing K^2 and the upper sealing roll L^2 . This lifting action need only be sufficient to release the pressure of the upper roll on the work so that the sealed can may be withdrawn and a new can with its cover be properly fed to the sealing rolls. As the strain on these parts is heavy owing to the strength of the spring K^2 against which they must act, it is desirable that these parts be made in one forging. The former which forms the upper part of the work-holder is lifted by a similar mechanism. H is the cam which engages the cam lever H^1 on the shaft H^2 at the proper time and gives the cam lever a slight turn which lifts an arm H^1 mounted on the other end of the shaft H^2 to cause it to engage the toe r^{10} on the clamping mechanism. This lifts the arm R^1 and the parts carried thereby and so releases the box. This action is of course automatic and the members of the work-holder remain in separated relation so long as the arm H^1 and the toe are in connection, during which time the box can be removed and a fresh piece of work put in its place. When thought desirable, however, the machine can be stopped by releasing the clutch treadle, a fresh piece of work put in place and by turning the handle r^2 the former or upper member of the work-holder can be dropped upon the cover by hand, this insuring the proper centering of the work, after which the machine may again be started up.

To guide the strip while it is being folded over the box to cover the edges we prefer to provide a roll w^2 mounted on the end of the lever w^1 fulcrumed in block w^3 mounted on the table A , the lever being held to its work by a spring w^4 . An adjustable stop w^5 limits the movement of the lever w^1 so that it will not be pulled materially out of place when the work is withdrawn. This lever also tends to throw the finished work out when the work-holder is opened and the roll also serves to prevent the bent surface of the strip from crimping or buckling during the attaching operation.

The modification shown in Figs. 20 and 21 relates to means for aiding the

lateral movement to the lower work-holder S . For this purpose a bracket S^2 is bolted to the under side of the table A and in this bracket is supported a shaft S^3 carrying at one end a gear S^4 and at the other end a bevel gear S^5 . The gear S^4 is in mesh with an intermediate gear S^6 mounted on a stud S^7 also supported by the bracket S^2 which gear is in mesh with the gear D^2 (see Fig. 21). S^8 is a vertical shaft carrying a bevel gear S^9 in mesh with the bevel gear S^5 . This gear S^9 is fast on the shaft S^8 and serves to support it in the arm S^{10} attached to the bracket S^2 . The shaft S^8 also carries a pinion S^{11} in mesh with teeth s^{12} on the periphery of a lower former S^{13} which is shaped like the upper form R^2 . The lower former S^{13} has a bearing to receive the stud S^9 to which it is attached by the set screw s^{14} and it is recessed to receive the roll s^2 carried by a stud s^3 set into a bearing s^4 on the arm s^5 attached to the bracket S^2 , this mechanism being identical in character with the mechanism formerly described in connection with the upper member of the work-holder.

In the operation of our machine the nut T^{14} is first unscrewed sufficiently to allow the feed rolls t^2 , t^3 to separate slightly, and the strip P is pushed between the guides W , W , the rolls t^2 , t^3 and the punch and die s^6 sufficiently far to be gripped by the rolls u^2 , u^3 . The nut T^{14} is then screwed sufficiently upon the part T^{15} to compress the spring T^{16} and close the rolls t^2 , t^3 against each other. This need only be done when a fresh strip is inserted. The machine is then started up and the strip is drawn in by the feeding and forming rolls until the cutting operation takes place, the first portion of the strip being perhaps wasted.

As described above the strip-feeding and forming operation is intermittent. It is caused by the movement of the rack in a direction to the right (see Fig. 1). After the first cutting operation the strip is fed by the feeding rolls and drawn by the forming rolls during the said movement of the rack, this movement carrying the front end of the strip up to the sealing rolls, which it reaches just after the upper sealing roll has been lifted. At this moment the work holder is opened for the reception of the work. The work being put in place and the upper work-holder having dropped upon the work, the upper sealing roll is released so that it comes down on the work pressing the strip and the flanges against the lower sealing roll. The sealing operation now begins, and after a short dwell the feeding and forming of the strip for the next box begins. When the work has completed its rotation the nut-tightenings of the intermediate gears become effective to stop the rotation of the work-holder and the sealing rolls and at the

The modification shown in Figs. 29 and 21 relates to means for giving a positive re-

work-holder separate and the work is ejected. The operation is then repeated. The modification operates in the same way.

What we claim as our invention is:—

5. 1. A box-sealing machine comprising a rotary work-holder, a strip-feeding mechanism, a strip-forming mechanism, a strip-stretching mechanism, and sealing rolls adapted to seal the strip upon the work.
10. 2. A box-sealing machine comprising a rotary work-holder, a strip-feeding mechanism, sealing rolls adapted to seal the strip upon the work, and a guide adapted to hold the strip against the work during the sealing operation, said parts during the sealing operation occupying relatively fixed positions in the machine.
15. 3. In a box-sealing machine, a work-holder comprising two members adapted to clamp a box and its cover between them one of said members having gear teeth about its periphery, means for rotating said work-holder comprising a shaft carrying a gear having elongated teeth in mesh with the teeth on said work-holding member, and means for automatically separating the said gear carrying member from the other member of said work holder to discharge the finished work and releasing it to clamp a
20. 4. In a box-sealing machine, two sealing rolls, a work-holder comprising two members and a guide adapted to hold a strip under said sealing rolls and against the work during the sealing operation, and means for separating the members of said work-holder, and means for separating said sealing rolls, said guide being adapted to eject the work when said work-holder members and said
25. 5. In a box-sealing machine, sealing rolls and means for feeding a sealing strip thereto comprising feed rolls, forming rolls and means for giving them an intermittent movement, and guides located to guide said strip from the forming rolls to the work, one of said guides having a straightening roll, as described.
30. 6. In a box sealing machine, a strip feeding mechanism comprising two shafts, a roll mounted on each shaft, the peripheries of said rolls being oppositely disposed to form a passage for the strip to be fed, and means for regulating the pressure of said rolls upon the strip comprising a cross piece having a bearing for one end of one of said shafts and a section of a bearing for the corresponding end of the other shaft, a slide piece completing the bearing of said last named shaft and adjustable yielding means

for holding said slide piece against said shaft and said shaft against said cross piece.

7. In a box sealing machine, a work holder comprising two members, one of said members being recessed, and driving and guiding connections for said work holder comprising teeth on said recessed member, a power member having teeth engaging said first named teeth, and means located to bear upon the interior of said recess to hold the teeth on said recessed member and power member in mesh, said recessed member being movable toward and from the other member to clamp and release the work and said parts being constructed and arranged to permit said movement without disturbing said driving connections.

8. In a box sealing machine, a work holder comprising two members, one of said members being recessed, and driving and guiding connections for said work holder comprising teeth on said recessed member, a power member having teeth engaging said first named teeth, and of greater length than said first named teeth, means located to bear upon the interior of said recess to hold the teeth on said recessed member and power member in mesh, said means being of less length than the depth of said recess, and means for moving said recessed member toward and from the other member to clamp and release the work.

9. In a box sealing machine, in combination with a strip feeding and attaching mechanism, a work holder having a rotary movement, means for rotating it, and jointed means for supporting said work holder whereby the axis of rotation thereof may be shifted and the edge of the work in its rotation be continuously presented to the attaching mechanism irrespective of the shape of said edge.

10. A box sealing machine comprising means for clamping and feeding the work, a strip feeding mechanism, a strip forming mechanism, and sealing rolls adapted to seal the strip upon the work and a spring controlled guide located to hold the strip in position to be acted upon by the sealing rolls and adapted to eject the work upon the separation of the clamping means.

11. A box sealing machine comprising a rotary work holder, a strip feeding mechanism, a strip forming mechanism, sealing rolls adapted to seal the strip upon the work, and a guide adapted to hold the strip against the work during the sealing operation, said guide comprising a lever carrying a guide wheel at one end thereof and means for holding said guide wheel against said work.

12. A box sealing machine comprising a rotary work holder, a strip feeding mechanism, a strip forming mechanism, sealing rolls adapted to seal the strip upon the work,

and a guide adapted to hold the strip against the work during the sealing operation, said guide comprising a lever carrying a guide wheel at one end thereof and means for causing said guide wheel to press against the edge of the work, and means for separating the members of the work holder whereby when said members are separated said guide

wheel will serve to eject the work as described.
